UNITED STATES PATENT OFFICE.

CHARLES F. STIGLITZ, OF LOUISVILLE, KENTUCKY, ASSIGNOR OF ONE-HALF TO
DANIEL R. STIGLITZ, OF LOUISVILLE, KENTUCKY.

DOOR FOR COAL-CHUTES.

1,242,067.

Specification of Letters Patent.

Patented Oct. 2, 1917.

Application filed April 23, 1915. Serial No. 23,280.

To all whom it may concern:

Be it known that I, CHARLES F. STIGLITZ, a citizen of the United States, residing in the city of Louisville, county of Jefferson, 5 and State of Kentucky, have invented a certain new and useful Improvement in Doors for Coal-Chutes, of which the following is a specification.

This invention relates to doors for coal chutes with special reference to that class of chutes placed in the walls of residences to facilitate the deposit of coal in the cellars or basements thereof.

An object is the provision of a door, of 10 the class described, the operative connections whereof lie within the chute, hence the working thereof will not be interfered with by conditions of the weather such as ice and sleet, nor are the hinge lugs, usually 15 of cast iron, liable to be broken off in cold weather as is the case with doors hinged exteriorly. Again in the case of doors having hinge lugs on the exterior, the lugs may be 20 readily broken off with a hammer and access thus afforded to the interior of the house.

A further object is the provision of a door which will be economical in construction, 25 easy of installation and durable in service.

With the foregoing and other objects in 30 view, the invention consists of the novel arrangement and construction of parts illustrated in the accompanying drawing which forms a part of this specification, wherein is set forth an embodiment of the invention, 35 but it is to be understood that such changes and modifications may be resorted to as come within the scope of the appended claims.

In the drawing wherein similar reference characters designate like parts in the several 40 views:

Figure 1, is a front elevation of a coal chute with an embodiment of my invention applied thereto showing the door closed;

Fig. 2, a rear elevation of the same showing the door open;

Fig. 3, a vertical section on line 1—1 of Fig. 1.

Fig. 4, a vertical section on line 2—2 of Fig. 2.

Fig. 5, a perspective view of the hinge member.

Fig. 6, a perspective of a modified form of a hinge member.

Referring to the drawing —11— designates a chute, usually of quadrangular 55 shape, adapted to be built in the wall of a building. It may be formed of any suitable material though preferably sheet iron is used as it may readily be bent to form the walls. Secured to the front end of the chute, 60 surrounding the mouth thereof, is a frame, or casing —12—. A door —13— fits in the frame, normally closing the mouth of the chute. Arms —14, 15— pivotally connected, 65 respectively with the door and with a wall of the chute, adjacent the front end thereof, provide means whereby the door may be swung from the closed to the open position, and conversely, the door at all times occupying planes substantially parallel with that 70 in which it lies when closed. As illustrated, the door swings forward, upward and backward to a position above the mouth of the chute where it is supported by suitable means, such as a lug —16— which projects 75 forward from the frame 12. The arms 14, 15 may be connected with the door and the chute in any suitable manner which will permit a relative pivotal or swinging movement thereof. As illustrated lateral projections —17— on the lower, or outer ends of the arms 14 and 15, are engaged in perforations —18— in lugs —19— which project from the inner surface of the door intermediate the extent thereof. The inner ends of 80 the arms are connected, or united, by an integral transverse member —20— and are positioned on the upper wall of the chute adjacent the forward end thereof by means of clips —21—. The arms 14, 15 are each 85 provided near their inner ends with a recessed, or curved portion —22— adapted to fit about, or receive the frame, when the door is swung open, permitting the rectilinear portions of the arms to assume a position 90 substantially parallel with the face of the frame.

It will be observed with the construction described that the door will be retained in a closed position by its own weight. 100 To prevent the door from being forcibly opened from the outside a lug —24— is provided on the lower edge of the door which is adapted to engage behind the frame when the door is closed. A spring latch —25— 105 positioned on the inner surface of the door,

near the upper edge thereof, is adapted to engage behind the frame, when the door is closed, whereby the door is securely held in the open position against any attempt at forcible entry from the outside. To open the door the latch is first released from the interior; a handle —26— on the outer face of the door is grasped and the upper edge of the door is swung out slightly, in order that the latch may clear the frame; the door is then lifted, the arms 14, 15 causing it to first swing forward, then as the arms pass the horizontal, backward until the lower edge of the door is just above the lug 16, projecting from the frame, when the lower edge is swung slightly rearward and the door lowered until it engages with the lug whereby it is held. A hopper comprising triangular sides —27— and a connecting base —28— is swung from pivots —29— in the side walls of the chute adjacent the top of the mouth thereof and is adapted to be drawn out when the door is opened. Depending projections —30— on the rear edge of the base are adapted to be engaged with the frame and hold the hopper in an extended position. The sides 27 are provided with slotted bearings —31— which are engaged over the pivots 29 and which permit the hopper to be raised to allow the projections 30 to clear the frame in swinging it in and out of the chute.

Having thus described my invention so

Copies of this patent may be obtained for five cents each, by addressing the "Commissioner of Patents, Washington, D. C."

that anyone may make and use the same, I claim:

1. In combination a vertically disposed door frame, an arm the inner end of which is pivotally connected interiorly of the frame, said arm comprising a curved portion and a rectilinear portion, said curved portion fitting about the inner edge of the frame whereby the rectilinear portion may extend above the frame exterior thereof in a plane substantially parallel with the face of the frame, a door to the inner surface of which the outer end of said arm is pivotally connected, and a lug projecting from the frame above the doorway whereon the lower edge of the door may be rested to hold it in its elevated or open position. 35

2. In combination, a vertically disposed door frame, a door adapted to close the opening therein, a lateral projection from the face of the frame immediately above the opening, arms pivotally connected respectively to the inner side of the door and to the interior of the frame at the upper portion thereof, said arms having a curved portion adapted to fit about the edge of the doorway whereby the door may be swung 50 to a position above the doorway with its lower edge supported on said lateral projection, in which position the door is substantially parallel to the position which it occupies when closed. 55

CHARLES F. STIGLITZ.
